TOY BOMBING PLANE

Louis T. E. Thompson, Dahlgren, Va., assignor of
one-third to Henry C. Parker, Washington,
D. C.

Application February 6, 1934, Serial No. 710,016

6 Claims. (Cl. 46—81)

This invention relates to toy bombing planes and it comprises a free flying toy glider or aeroplane carrying a bomb, with means for releasing said bomb while said aeroplane is in undisturbed flight and after a predetermined time interval or after a predetermined distance of flight, the said bomb being adapted to hit a target; all as more fully set forth and as claimed.

In the prior art various toy bombing planes have been suggested. U. S. Patent No. 1,912,925, for example, describes a plane designed to be carried by the operator with various bomb releases which are tripped by hand. My prior U. S. Patent No. 1,924,261 describes an aeroplane usually mounted on a tower with a bomb designed to be dropped upon a moving target. Other toy aeroplanes have been mounted on swinging arms or have been suspended from wires, with various means being provided for the release of toy bombs. In none of these prior art devices has provision been made for the dropping of a bomb at a predetermined point with the toy plane in undisturbed full flight.

Other toys have been designed to release parachutes. U. S. Patent No. 1,821,172, for example, releases a parachute when its momentum is lost and just before the wings of the aeroplane open. In the design of Patent No. 1,845,613 a parachute is shot out when the nose of the plane hits an obstruction. Even in these aeroplane-parachute toys there has been no provision for release of a toy element from a plane in undisturbed flight.

In none of the bombing plane toys nor in the parachute-plane toys has any means been described for the release of a toy element after a predetermined time interval or after a predetermined distance of flight. None of these toys therefore can be used in the bombing game which I have invented.

In this game a toy aeroplane or glider is employed which carries a bomb capable of being released at a predetermined point with the toy plane or glider in full flight. The bomb is adapted to hit a target which is provided and which may be moving or stationary. Thus a competitive game is provided which affords many of the thrills and requires much of the skill of the true bombing attack.

In the accompanying drawing I have shown, more or less diagrammatically, several advantageous embodiments of my toy bombing aeroplane which fall within the purview of my invention and are capable of use in the described game.

In this showing:

Fig. 1 is a perspective view of my toy bombing glider ready to be released from a tower with a target in front of and below the point of release.

Fig. 2 is an enlarged view in elevation of one form of bomb and bomb release mechanism.

Fig. 3 is a longitudinal sectional view of the bomb shown in Fig. 2, taken along the line 3—3.

Fig. 4 shows a modified form of bomb and of bomb release mechanism.

In the various figures like elements are designated by like reference numerals. Referring to Fig. 1, element 1 represents a toy bombing glider which is shown resting on a platform 2. The platform is mounted on four posts 3 which are supported by a base 4. The glider itself is of known construction but is provided with a bomb 5.

The glider shown in Fig. 1 is designed to be shot from the platform 2 by a rubber band 6 which engages a notch 7 provided in the body 20 of the glider. The glider is released by merely pulling it backwardly by its tail and letting go when sufficient tension is obtained in the rubber band.

In Fig. 1 there is also shown a target 18 over which the aeroplane is intended to fly as the bomb 5 is dropped. This target may be provided with a sheet of percussion caps 19 which explode upon being struck by the bomb. This target may, of course, be provided with a bull's eye and circles, 30 each circle being given a number representing a score. My game may then be played and scored much like a competition on a rifle range.

The details of one form of bomb mounting are shown in Fig. 2. In this figure, the bomb is held within a cut away section 8 of the body of the glider. It is supported by a cord 9, which may be wrapped around the body of the bomb any number of times, the end being then slipped under a spring clip 10, or in a slit cut in the wood of the body of the glider.

The bomb itself may be of simple construction as best shown in Fig. 3. An outer cylindrical casing 11 is provided, this casing being constricted at one end as shown at 12. Within the casing a ball bearing 13 is provided which fits the casing loosely but is too large to pass through the constriction 12. The other end of the casing is closed by a stopper 14, at the end of which a vane or feather 15 may be attached. Within the casing there is a steel cylinder or anvil 16, and between this anvil and the ball bearing 13, there may be placed a toy percussion cap 17.

If desired the structure shown in Fig. 2 can be modified by the inclusion of side shields on both 55

sides of the bomb to help conceal the bomb and to form a pocket in which the bomb may be carried.

In Fig. 4 a modified bomb is shown as well as a modified method of releasing the same. In this embodiment a pulley 20 is provided, upon which is wound a cord 9. This cord is attached to the bomb 5 at one end while the other is provided with a knot which is slipped into a notch 21 on the rim of the pulley. The bomb shown in Fig. 4 is closed at its lower end which terminates in a point 22. It may also be provided with a steel cylinder anvil 16 and a cap 17. With this type of bomb it is desirable to employ a target which is of soft material, such as cork with the exception of a bull's eye which is of harder material.

The cap will then explode only when the bull's eye is struck. Otherwise the point 22 will merely penetrate the target breaking the fall of the bomb 20 sufficiently to prevent explosion.

The bombs shown in Figs. 2 and 4 are released in much the same manner. The weight of the bomb shown in Fig. 2 causes it to unwind the cord and to finally drop freely. The number of turns of cord around the bomb determines the time of release. The feather 15 rights the bomb in the air and it strikes on the ball bearing 13. In the case of the bomb shown in Fig. 4, the weight of the bomb causes the cord to unwind 30 from the pulley. The cord is released and the bomb drops freely as soon as the cord is fully unwound and when the knot on the end has slipped out of the notch 21. In this case the cord acts like a feather, keeping the bomb vertical during flight.

With the embodiments shown in Figs. 1, 2 and 4, the bomb drops at a predetermined time interval after the take-off. In these devices the speed of the plane does not affect the release of the bomb.

While I have described what I consider the best embodiments of my invention, there are many modifications which still fall within the purview of the same. For example, the plane; 45 that is the aeroplane or the glider modification; may be released from the hand, from a tower or from the ground. Many different methods of releasing the bombs may be employed; these methods advantageously providing release after a predetermined time interval or after a predetermined distance of flight. Many different types of bombs may be employed. For example, I have even found a simple dart effective, this dart being provided with a sharp point at one end and a

feather at the other. A simple form of bomb is a small bag of shot which will remain approximately where it strikes without sliding or rolling. Any type of toy glider or aeroplane may be employed. Targets of any description are suitable. 5 These are advantageously provided with rings or areas representing different scores by means of which a competitive game may be played. Various other modifications falling within the scope of my invention will be evident to those skilled 10 in the art.

What I claim is:

1. In combination, a free flying toy bombing plane, a bomb carried by said plane, a cord secured to said plane and wrapped around said bomb adapted to temporarily hold said bomb to said plane and to gradually unwrap to release said bomb at a predetermined point while said plane is in full flight, a target adapted to be struck by said bomb and means provided on said target for 20 causing a detonation upon the striking of said target by said bomb.

2. In combination, a free flying toy bombing plane, a miniature bomb, a cord wrapped with a plurality of turns around said bomb and attached 25 to said plane, said cord being adapted to unwind from said bomb thereby releasing the same while said plane is in full flight and in time relation to the number of turns of cord wrapped around said bomb.

3. In combination, a free flying toy bombing plane, a miniature bomb, a cord attached to said bomb and means mounted on said plane for temporarily holding said cord by means of a plurality of turns of said cord and for automatically 35 releasing the same at a predetermined point, thereby also releasing said bomb while said plane is in full flight and in time relation to the said turns of said cord.

4. In combination, a free flying toy bombing plane, a cord and a miniature bomb temporarily secured to said plane by a plurality of turns of said cord, said cord being adapted to gradually 45 unwind thereby releasing said bomb while said plane is in full flight and in time relation to the number of turns of said cord which secure said bomb to said plane.

5. The device of claim 4 in further combination with a tower for setting said plane in flight.

6. The device of claim 1 wherein the said target 50 comprises a hard surface and said bomb is adapted to detonate upon striking such a surface.

LOUIS T. E. THOMPSON.
